RADIATOR CORE

Laurence P. Saunders, Lockport, N. Y., assignor
to General Motors Corporation, Detroit, Mich.,
a corporation of Delaware

Application December 29, 1934, Serial No. 759,659

4 Claims. (Cl. 257—130)

This invention relates to heat exchangers and particularly to an improved automobile radiator core construction.

It is an object of the invention to provide a core construction wherein the spaced water tubes for the flow of cooling medium are formed each from a pair of substantially flat plates placed face to face for the flow therebetween of heat exchanging medium in thin streams and on straight lines. The thin stream flow insures the quick transfer of heat and the straight line course reduces resistance to free passage and clogging of the tube by the entrapment of foreign material therein.

A further object of the invention is to provide a simplified tube plate design free of complicated formations and which can be made at low cost and when assembled with a number of similar tube plates joins with the next succeeding plate on one side to form a closed water tube and with the next succeeding plate to the other side to form an air space. To this end the tube plates, made to be interchangeable, are preformed each with portions along both edges offset inwardly with respect to the resulting tube for spacing the plate proper from the mating plate, one of the offset edge portions being somewhat wider than the other so that it can be reversely bent over the narrow offset edge of the mating plate to seal and join the edges. In addition, the end portions of each plate are devoid of deformations and are bent outwardly each on a straight line across the flat end portion for overlapping attachment with a corresponding portion of the adjacent plate of the next succeeding tube. In this way the several plates are joined together as a single unit.

Another object is to provide an improved arrangement of cooperating fin strips associated with the tubes and located in the spaces between succeeding tubes. The fin strip consists of a series of angularly related sections which alternately bear in flat contact with opposite tube walls for attachment thereto and extend across the space to constitute heat radiating fins, and the fin strip not only increases heat radiating surface but also strengthens the tube walls and holds them apart a definite distance. Additional inward offsets extending longitudinally of the tube walls serve to space the intermediate portion of the tube against inward collapse and at the same time provide recesses to seat locating projections on the wall engaging sections of the fin strip, whereby the parts are secured against accidental displacement.

Additional objects and advantages of the construction involved will become apparent during the course of the following detail description having reference to the accompanying drawings in which Figure 1 is a perspective view of a 5 sloping radiator embodying the invention; Figures 2 and 3 are, respectively, a vertical longitudinal section and a transverse horizontal section of fragments of the core structure; Figure 4 is a perspective view of one of the sloping water 10 tubes and its associated fins; Figure 5 is a perspective view similar to Figure 4, but showing the invention incorporated in a vertically disposed water tube; Figure 6 is an enlarged sectional view on a transverse vertical line at one 15 end of the assembly; and Figure 7 is an enlarged section through one edge of a tube.

The invention is particularly adaptable for use with a sloping radiator, as shown in Figure 1, where the numeral 1 indicates the core 20 assembly connecting the top and bottom tanks 2 and 3 which are longitudinally offset with relation to each other. In addition to the rearward inclination, the core is of V-shape or in other words its front and rear faces diverge 25 rearwardly from the vertical center line of the assembly. Consequently the water tubes are downwardly inclined between the top and bottom tanks while the heat radiating fins extend along lines substantially horizontal or in the 30 direction of the incoming air stream, as is shown particularly in Figure 2.

Each water tube 4 comprises a pair of substantially flat plates extending on a straight line from the top to the bottom of the core. 35 Following lines extending longitudinally of each plate and spaced transversely from the front and rear edges are one or more inwardly pressed ridges or offsets 5 and the offsets of one plate cooperate with corresponding offsets of the other 40 plate to hold the tubes against inward collapse. Along each edge of the strip are additional offsets 6 and 7 for spacing and joining the plates. The offset edge portion 6 is considerably wider 45 than the offset 7 along the opposite edge and when two such similarly formed plates are placed together the narrow offset 7 of one abuts the wider offset 6 of the other as seen in Figure 7, and the additional material in the wider edge 50 is reversely bent over the abutting edge to provide a lock seam. The wall strips joined together at their edges thus provide a closed tube having straight sides and an interior hollow space that defines a straight line course from 55

one end to the other, and which is divided into sections by the spacer ribs 5.

The spacer ribs 5 extend throughout the length of the tube but terminate short of the ends of the wall plate as do also the offset edge portions 6 and 7. The resulting flat end portions are turned outwardly as at 8, the line of bending 8' being across but within the flattened portion so as to afford a smooth bend and one which is easy to make. As shown in Figure 6 the end portion 8 of one tube overlaps the corresponding end portion of the adjacent wall of the next succeeding tube and may be secured thereto by a soldering operation to unite the several tubes.

The fin strip involves a succession of angularly bent portions of which those indicated by the numeral 9 afford heat radiating fins that extend across the space between the tubes, and the portions 10 connecting the fins provide flat wall engaging surfaces for the ready transfer of heat from the wall into the fins. The flat wall engaging sections 10 are preferably provided with bulges or projections 11 alined with 25 and projecting into the inwardly extending ribs 5 of the wall strips whereby to interlock the parts against fore and aft separation. As shown in the drawings the fins 9 may be provided with louvered openings 12 for dividing and deflecting 30 air particles from one cell to the next to insure wiping contact with the metal surfaces of a maximum number of air particles.

When applied to a sloping radiator core construction the successive fins will be arranged 35 successively in longitudinally offset relation in conformity to the inclination of the tubes, as illustrated in Figure 2, but the direction of the fins should be maintained to conform with the direction of the incoming air stream. When 40 the parts are embodied in a V-type radiator the succeeding water tubes and fin strips are merely arranged successively in transversely offset relation as illustrated in Figure 3. The arrangement of the parts in a flat face vertical core is seen in Figure 5.

For joining the fins to the flat water tube surfaces the exterior of the water tubes may be pretinned and the assembly placed in an oven to insure a good surface bond. Alternately 50 a thin strip of solder foil may be interposed between the surfaces to be joined, which upon the application of heat will melt and run between the abutting surfaces.

I claim:

55 1. In a heat exchanger, a plurality of spaced tubes, each comprising a pair of mating strips having flat end portions bent outwardly each on a line within the flat portion, for overlapped attached relation with a corresponding portion 60 of the next adjacent tube, each strip between said end portions and throughout its length providing a straight side wall of the tube and having therein at transversely spaced intervals a series of spacer ribs pressed inwardly along longitudinally straight lines for seating engagement with corresponding spacer ribs of the

5 mating wall strip, and having its margins along opposite edges offset inwardly with one thereof wider than the other and reversely bent over the narrower offset margin of the mating strip, and a spacer strip between each pair of succeeding tubes comprising a succession of angularly bent portions, every other one of which constitutes a fin extending across the space between the tubes, with those portions between the fins in flat seating engagement in alternate 10 relation with adjacent walls of the spaced tubes, and provided with outward bulges alined and interlocked with the inwardly pressed ribs of abutting wall strips.

2. In a heat exchanger, a series of spaced tubes 15 straight sided from end to end, each comprising a pair of mating wall strips having flat end portions, each bent outwardly on a line within the flat end portion, for attachment with a corresponding flat end portion of an adjacent tube 20 strip, inwardly pressed longitudinal spacer ribs extending on a straight line between said end portions to hold the strips apart, and inwardly offset margins along each edge, one of which is reversely bent over the other, and heat radiat- 25 ing fins having flat surface engagement with both of succeeding pairs of tubes.

3. An automobile radiator assembly including 30 a pair of spaced tanks offset longitudinally from one another, a series of spaced tubes extending at an incline between the offset tanks for the flow of cooling medium in thin streams, each tube comprising a pair of juxtaposed plates having flat wall portions extending each in a single plane on a straight line between the tanks and having inwardly offset and longitudinally extending beads for spacing the wall portions apart, and a fin strip between succeeding pairs of tubes, comprising a series of angularly bent sections 35 with alternate sections extending across the space between the tubes to constitute fins and succeeding fins being longitudinally offset from one another in conformity with the inclination of the tubes, but extending along lines substantially conforming with the direction of the incoming 40 air stream, and the connecting portions between the fins in flat surface contact with adjacent plates and provided with alining projections fitting into said inwardly offset beads.

4. An automobile radiator assembly, including 45 50 a pair of headers spaced vertically and longitudinally of each other, a series of transversely spaced straight sided tubes extending in inclined relation between the tanks and being successively offset from one another rearwardly 55 from the longitudinal center line of the assembly, and a succession of vertically spaced fins in the spaces between the tubes, each fin being offset vertically from the next adjacent fin to conform with tube inclination and extending longitudinally of the assembly and diagonally in relation to the inclination of said tubes 60 for cooperation with adjacent fins to provide substantially horizontal air cells.
